UNITED STATES PATENT OFFICE.

PEMBROKE D. HARTON, OF PHILADELPHIA, PENNSYLVANIA, ASSIGNOR OF
TWO-THIRDS TO CHARLES K. BULLOCK, OF SAME PLACE.

SAFETY ATTACHMENT FOR ELEVATORS.

SPECIFICATION forming part of Letters Patent No. 255,110, dated March 21, 1882.

Application filed August 9, 1881. (No model.)

To all whom it may concern:

Be it known that I, PEMBROKE D. HARTON, of the city and county of Philadelphia, in the State of Pennsylvania, have invented an Improvement in Safety Attachments for Elevators, of which the following is a specification.

My invention has reference to safety attachments for elevators; and it consists in dispensing with the spring heretofore used to throw the clutch-levers into the racks when the cable should break, and in lieu thereof using a positively-operating device consisting of a cable attached at the bottom to the latching device, and passing over a deeply-grooved idler-wheel at the top, and attached to a weight; further, in a brake or friction band adapted to be put in action to retard the revolution of the idler-pulley or wheel upon the breaking of the elevating-cable; and in minor details of construction, all of which are fully set forth in the following specification and shown in the accompanying drawings, which form part thereof.

The object of this invention is to insure the arrest of the falling cage by providing a positive checking device in lieu of the spring heretofore used. By the construction herein set forth the greater the fall of the cage the greater is the force exerted to throw the clutch-levers into contact with the racks secured to the guide-posts.

Heretofore springs have been used to pull down the long ends of the levers upon the elevating-cable being severed, which action forced the short ends of the levers into the rack-teeth. In practice, however, it is found that in many cases the springs lose their power after being compressed for a long time, and will not work. In this case no spring is used, and the checking device is only thrown into action upon the breaking of the elevating-cable.

In the drawings, Figure 1 is an elevation of an elevator embodying in it my invention. Fig. 2 is a modification of the means by which the checking-cable is connected to the latching or safety mechanism. Fig. 3 is an elevation of the idler-wheel over which the checking or safety cable passes.

A A are the guide-posts, and are furnished

with the usual racks, B B. The elevating-cable D passes over the sheave P and supports 50 the cage C, which is furnished with the usual safety-levers, E, which are thrown in and out of action with the rack-teeth by the piece F, which is connected at the top to the cable D and at the bottom to the lever G by link H. The 55 other end of said lever G is connected to the safety-cable I, which passes over the idler-wheel K at the top, and is secured to a weight, J, whereby the cable is pressed into the V-groove k on the face of the wheel K. 60

If desired, the cable I may pass around a wheel, G', and be directly connected to the safety-levers or the piece F, the wheel being merely one form of the lever shown in Fig. 1.

The idler-wheel K is provided with a friction-flange, L, which is wholly or partly encircled by the brake-band M, one end of which is secured to the post A and the other end to the lever N, which is pivoted at n, and carries on its long end an idler-wheel, O, provided 65 with a deep groove. The lever N is arranged 70 at an oblique angle, and the roller O rests against the cable D, allowing the latter to move up or down without moving the lever.

The operation is as follows: If the cable D 75 should break, the lever N drops down and puts the brake M on the wheel K, arresting its movement, whereupon the cable I pulls up the end of the lever G and forces the teeth of the safety-levers E into the teeth of the racks B, arresting 80 the descending cage C. The groove k in the wheel K is made acute enough to make the cable I bind tightly therein should the wheel be held from revolution.

The brake is not necessary to my invention, 85 yet I prefer to use the same, as it renders the elevator safer.

While ordinarily running the weight J has not sufficient power to put the safety-teeth in action, and as the brake is off the wheel K the 90 cable I travels back and forth over the said wheel as the cage ascends and descends.

I do not limit myself to any particular safety-latch, as my invention is equally adapted to insure proper action to several of such latches 95 in public use; but I prefer the one shown.

Having now described my invention, what I claim as new, and desire to secure by Letters Patent, is—

1. A safety attachment for elevators, consisting of a cable, one end of which is secured to and combined with the latching mechanism adapted to arrest the descending cage, and the other to a weight, in combination with a grooved wheel, over which said cable travels upon the ascent or descent of the cage, a brake to arrest or retard the rotation of said grooved wheel, and means to put said brake in action upon the falling of the cage, substantially as and for the purpose specified.
2. In a safety attachment for elevators, the

sheave P, elevating-cable D, cage C, with its safety-latch, in combination with the safety-cable I, means to connect said cable with the latch, grooved pulley K, weight J, lever N, carrying on its end an idler-pulley, O, and a brake 20 adapted to be operated by any movement of said lever to arrest the movement of the grooved pulley, substantially as and for the purpose specified.

In testimony of which invention I hereunto set my hand.

PEMBROKE D. HARTON.
